(57) **CLAIM**

We claim the ornamental design for a mount bracket assembly for agricultural row unit, substantially as shown and described.

DESCRIPTION

FIG. 1 is a front perspective view of the mount bracket assembly for an agricultural row unit according to the present invention.

FIG. 2 is a rear perspective view of the mount bracket assembly.

FIG. 3 is a front elevation view of the mount bracket assembly.

FIG. 4 is a rear elevation view of the mount bracket assembly.

FIG. 5 is a left side elevation view of the mount bracket assembly.

FIG. 6 is a right side elevation view of the mount bracket assembly.

FIG. 7 is a top plan view of the mount bracket assembly.

FIG. 8 is a bottom plan view of the mount bracket assembly; and,

FIG. 9 is a perspective view showing the mount bracket assembly on an agricultural row unit, with structure shown in broken lines not being a part of the claimed invention.
